US00D972056S

(12) United States Design Patent (10) Patent No.: US D972,056 S
(45) Date of Patent: * Dec. 6, 2022

(54) COLLAR

(71) Applicant: Coulter Ventures, LLC., Columbus, OH (US)

(72) Inventor: Dylan Jones, Santa Barbara, CA (US)

(73) Assignee: Coulter Ventures, LLC., Columbus, OH (US)

() Term: 15 Years

(21) Appl. No.: 29/749,449

(22) Filed: Sep. 4, 2020

Related U.S. Application Data

(63) Continuation of application No. 29/671,985, filed on Nov. 30, 2018, now Pat. No. Des. 895,745.

(57) CLAIM

The ornamental design for a collar, as shown and described.

DESCRIPTION

FIG. 1 is a top, front, right perspective view of a collar showing my new design in a first position;

FIG. 2 is a top, front, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a cross-sectional view at 9-9 in FIG. 7 thereof;

FIG. 10 is a top, front, right perspective view of a collar showing my new design in a second position;

FIG. 11 is a top, front, left perspective view thereof;

FIG. 12 is a front view thereof;

FIG. 13 is a rear view thereof;

FIG. 14 is a right side view thereof;

FIG. 15 is a left side view thereof;

FIG. 16 is a top view thereof;

FIG. 17 is a bottom view thereof;

FIG. 18 is a cross-sectional view at 18-18 in FIG. 16 thereof;

FIG. 19 is a top, front, right perspective view of a collar showing my new design in a third position;

FIG. 20 is a top, front, left perspective view thereof;

FIG. 21 is a front view thereof;

FIG. 22 is a rear view thereof;

FIG. 23 is a right side view thereof;

FIG. 24 is a left side view thereof;

FIG. 25 is a top view thereof;

FIG. 26 is a bottom view thereof; and,

FIG. 27 is a cross-sectional view at 27-27 in FIG. 25 thereof.

The broken lines in the drawings are for the purpose of illustrating portions of the collar, which form no part of the claimed design.

1 Claim, 27 Drawing Sheets
